UNITED STATES PATENT OFFICE.

ARTHUR E. HOLMES, OF PITTSFIELD, MASSACHUSETTS, ASSIGNOR TO EATON, CRANE & PIKE CO., OF PITTSFIELD, MASSACHUSETTS, A CORPORATION OF MAINE.

MACHINE FOR USE IN APPLYING PAPER COVERINGS OR COATINGS TO PAPER BOXES.

1,237,250.

Specification of Letters Patent. Patented Aug. 14, 1917.

Application filed September 28, 1915. Serial No. 53,037.

To all whom it may concern:

Be it known that I, ARTHUR E. HOLMES, a citizen of the United States of America, residing in Pittsfield, in the county of Berkshire and State of Massachusetts, have invented certain new and useful Improvements in Machines for Use in Applying Paper Coverings or Coatings to Paper Boxes, of which the following is a specification.

10 This invention relates to improvements in machines for use in applying paper coverings or coatings upon articles such as paper boxes or the like, and aims to provide improvements therein.

15 Paper boxes are usually made of pasteboard, and the top or bottom, and sides, covered with paper, frequently a decorated or good grade of paper. The bottom of the box is some times covered with a different 20 grade and weight of paper than the sides or other parts. Furthermore, a strip of paper for covering the top and bottom, of a different width than the strip of paper used for covering the sides, is usually necessary, and 25 hence the covering paper is usually taken from a plurality of rolls.

The present invention provides a machine or device, by the use of which the applying of the paper coatings to the boxes is much 30 facilitated, the operation of covering the box being simplified, shortened and cheapened. Other features of improvement will be hereinafter pointed out.

The invention will be described more fully 35 in connection with the accompanying drawings, wherein—

Figure 1 shows a side elevation of the machine;

Fig. 2 shows an end elevation (the box 40 mandrel at the end of the machine, however, being omitted);

Fig. 3 is an end view on an enlarged scale;

Fig. 4 is a partial sectional view on the line 4—4, Fig. 2.

45 In said drawings, numeral 1 designates a mandrel upon which the paper box X to be covered, is placed. Y designates a strip of paper for covering the top or bottom of a box, and Z designates a strip of paper for 50 covering the sides of the box.

In applying the paper coverings to the box, it is most convenient to have the top or bottom of the box uppermost when applying the top or bottom covering, and to have the 55 box on its sides when applying the side cov-

erings thereto. To this end the mandrel 1 is preferably mounted upon a trunnion 2 journaled in a hub 3 carried upon an arm 4. The mandrel 1 is preferably removable from the trunnion 2, to permit the machine to be 60 used in applying coverings to boxes of different size and shape. The arm 4 is supported in a bearing 5 carried by a rod 6 (Fig. 3). The rod 6 is slidable crosswise of the machine in bearings 7, 7. A slot 8 in a 65 plate attached to the machine, prevents the rod 6 from turning on its axis. A collar 9 may be provided for limiting the axial movement of the shaft 4.

A spring 10 acts on the shaft 6 in such 70 manner as to normally keep the mandrel in its upright position, as in Fig. 1. The axial movements of the shaft 6 are limited to the proper degree by the collars 11.

The turning of the shaft 4, to effect the 75 turning of the mandrel 1 from the position shown in Fig. 1 to that shown in Fig. 4, is preferably accomplished by means of a treadle 15. The shaft 4 has splined thereto a gear 16. The treadle is connected to the 80 gear by a rod 17. Upon pressing upon the treadle 15 to turn the gear 16, the gear 16 meshes with a rack 18, and the rod 6, carrying the bearing 5, is moved axially (to the right) at the same time that the shaft 4, 85 carrying the mandrel 1, is turned. The axial movement of the shaft 6 has the effect of bringing the mandrel 1 in substantially the same position axially of the machine, as was the mandrel prior to being turned. A 90 spring-catch 19 serves to hold the treadle 15 in its depressed position.

The roll of paper from which the strip Y unwinds is mounted in a suitable hanger 25. The strip of paper Y on unwinding passes 95 over a gluing roller 26 dipping in a glue pot 27, and one surface of the paper receives a coating of glue. After passing the gluing roller the strip of paper passes through a doctor 28 which removes the surplus glue. 100 The doctor may conveniently comprise a rod 29 frictionally held in its bearings, having one or more scraper bars 29' thereon. The strip of paper then passes over one or other of the rollers 30 on the vertical frame 31. 105 After passing over the rollers 30 the strip Y passes under a roller 33 and over a roller 35 suspended respectively in brackets 34, 36. The strip of paper then passes through another doctor 38, which acts to scrape off any 110

surplus glue which may be on the strip at this point, the drippings being received by a drip pan 39 beneath the doctor. The strip then passes beneath a guide or separator bar 40, and from thence over a cutter bar 41. At this point the strip of paper may be pulled forward by the operator and applied to the box, as hereinafter explained.

The roll from which the strip of paper Z comes, may be mounted in a hanger 50, the strip passing over a gluing roller 51 dipping in the glue pot 52, thence passing through a doctor 53 which acts to scrape surplus glue from the strip, and then passes over one or the other of the rollers 55 on the vertical frame 56. From thence the strip passes over the guide or separator bar 40, and from thence over the cutter bar 41, where it may be pulled forward by the operator, and used as hereinafter explained.

The hangers 25 and 50, brackets 34 and 36, glue pots 27 and 52, and vertical frames 31 and 56, may be conveniently mounted upon a pair of bars 60 running longitudinally of the machine and supported upon posts 61.

Operation: In applying the paper coverings to the box, the sides are usually covered first. The mandrel 1 is turned upon its side, by depressing the treadle 15 which rotates the gear 16 splined upon the shaft 4. The shaft 4 receives a rotation of 90°, and is held in this position by the catch 19 coming into engagement with the treadle. The strip of paper Y is pulled forward, the front edge placed at one of the corners of the box, and the box and mandrel rotated until it makes a full turn. A treadle 70 is then depressed, which acts through a rod 71 upon a pivoted knife 72 to sever (in conjunction with the cutter 41) the strip of paper Z. The detached end is then applied to the box. When the margins of the strip are wider than the box, the margins are turned over the edges of the box and pressed against the inner sides or bottom of the box.

The treadle 15 is then disengaged from the catch 19, and the spring 10 on the shaft 6 acts to rotate the shaft 4 back 90° to the vertical position shown in Fig. 1. The strip of paper Z is then pulled forward, and when a sufficient length has been pulled forward, the treadle 70 is again depressed to cause the cutter 72 to sever the strip Z.

In order that the portion severed for the top or bottom of the box may be of the right length, an adjustable stop 80 is provided. The rod 4 is slid in the bearing 5 until the side of the box comes against the stop 80. The severed portion of the strip Z will then be of the right length to cover the bottom of the box. Moreover, when the mandrel is on its side the severed strip of paper will be of substantially the appropriate length to lap at the edges after passing around the box.

As the strip Y is run off more rapidly

than the strip Z, and has less periods of rest, the gluing roller 26 is preferably placed at a greater distance from the cutter bar 41 than the gluing roller 51 which applies glue to the strip Z. By this arrangement a more uniform tempering of the glue upon the strips is accomplished.

In order to vary the tempering of the glue applied to the strips, the distance which the respective strips Y and Z travel between the gluing rolls and the cutter bar may be varied by passing the strips over one or the other of the rollers 30 or 55. Differences in the character of the paper, among other things, may occasion a difference in the degree of tempering which the respective strips require.

The inventive ideas may receive other mechanical expressions than those specifically illustrated and described.

I claim as my invention:

1. A machine of the character described, comprising a mandrel for holding a box in position to have coverings applied to its top or bottom, and sides, said mandrel being adapted to be turned to upright position or to a position on its side, and means for supporting a plurality of separated superposed paper strips adapted to be applied to the top or bottom, and sides, of the box on the mandrel, said mandrel in its upright and side positions being adapted to take up a position which is centered with respect to the strips which are to be applied.

2. A machine of the character described, comprising a mandrel for holding a box in position to have coverings applied to its top or bottom, and sides, means for supporting a plurality of separated superposed paper strips adapted to be applied to the top or bottom, and sides, of the box on the mandrel, and means for turning said mandrel from one position to another, one position being an upright position and the other position being a position on its side, said mandrel in its upright and side positions being moved to a position which is centered with respect to the strips which are to be applied.

3. A machine of the character described, comprising a mandrel for holding a box in position to have coverings applied to its top or bottom, and sides, said mandrel being adapted to be turned to upright position or to a position on its side, and means for supporting a plurality of separated superposed paper strips adapted to be applied to the top or bottom, and sides, of the box on the mandrel, said mandrel in its upright and side positions being adapted to take up a position which is centered with respect to the strips which are to be applied, said mandrel being mounted upon a rotatable support, and being rotatable in said support, and means for rotating said support for

bringing said mandrel from one position to another, one position being an upright position and the other position being a position upon its side.

- 5 4. A machine of the character described, comprising a mandrel for holding a box in position to have coverings applied to its top or bottom, and sides, and means for turning said mandrel from an upright position to 10 a position on its side, said mandrel in its upright and side positions, taking up a position which is substantially centered with relation to a common mid-plane.
5. A machine of the character described, 15 comprising a mandrel for holding a box in position to have coverings applied to its top or bottom, and sides, and means for turning said mandrel from an upright position to a position on its side, said means comprising 20 a rotatable support for the mandrel, a gear on said support, a rack on a fixed part of the machine, and a treadle connected to said gear and adapted to turn said gear to simultaneously turn said support and displace it 25 transversely of the machine.
6. A machine of the character described, comprising a mandrel for holding a box in position to have coverings applied to its top or bottom, and sides, and means for turning said mandrel from an upright position to 30 a position on its side, said means comprising a rotatable support for the mandrel, said support being movable axially of the machine, a gear splined on said support, a rack 35 on a fixed part of the machine, and a treadle connected to said gear and adapted to turn said gear to simultaneously turn said support and displace it transversely of the machine.
- 40 7. A machine of the character described, comprising a mandrel for holding a box in position to have coverings applied to its top or bottom, and sides, said mandrel being adapted to be turned to upright position or 45 to a position on its side, and means for sup- plying a plurality of superposed separated strips of glued paper, including a glue-applying device for each strip of paper, and means

for varying the length of the strips of paper between the glue-applying device and 50 the mandrel, whereby the degree of tempering of the glue on the several sheets of paper may be regulated.

8. A machine of the character described, comprising a mandrel for holding a box in 55 position to have coverings applied to its top or bottom, and sides, said mandrel being adapted to be turned to upright position or to a position on its side, and means for supplying a plurality of superposed separated 60 strips of glued paper, one of which serves for covering the sides and another for covering the top or bottom, a plurality of glue-applying devices, one strip of paper being of greater length between the glue- 65 applying device and mandrel than another strip of paper between its glue-applying device and the mandrel.

9. A machine of the character described, comprising a mandrel for holding a box in 70 position to have coverings applied to its top or bottom, and sides, said mandrel being adapted to be turned to upright position or to a position on its side, means for supporting a plurality of separated superposed paper strips adapted to be applied to the top or bottom, and sides, of the box on the mold, 75 said mandrel in its upright and side positions being adapted to take up a position which is centered with respect to the strips 80 which are to be applied, a cutter for severing portions of the paper from said strips, the position of the mandrel being adjustable with relation to the cutter, and means for stopping the mandrel in a position of 85 adjustment, whereby a piece of paper may be pulled over the cutter to a predetermined position on the box and severed, and the severed portion be of the appropriate length.

In witness whereof, I have hereunto 90 signed my name in the presence of two sub- scribing witnesses.

ARTHUR E. HOLMES.
